UNITED STATES PATENT OFFICE.

GEORGE L. GRIFFITH, OF NEW YORK, N. Y.

MOTOR-STARTING AND SAFETY DEVICE.

1,290,737.

Specification of Letters Patent.

Patented Jan. 7, 1919.

Application filed March 13, 1918. Serial No. 222,099.

To all whom it may concern:

Be it known that I, GEORGE L. GRIFFITH, a citizen of the United States of America, residing at New York city, county and

5 State of New York, have invented a new and useful Motor-Starting and Safety Device, of which the following is a specification.

10 My invention relates to the starting of internal combustion motors, and the objects of the invention are to provide relatively simple and inexpensive mechanism for this purpose and which can be readily applied to motor cars now in common use.

15 Other objects of the invention are to do away with expensive and complicated parts, electric wiring, etc., and further, to provide mechanism which will be positive in its operation.

20 Another object of the invention is to eliminate the danger of "back-kick" and to provide a device which will be entirely safe and can be operated by anyone.

Briefly, the invention comprises a starting 25 pulley which is connected with the motor shaft through a one-way drive connection and is operated by a cable connected with a suitable foot pedal or the like, said starting pulley being mounted on a shaft disposed concentrically to the motor shaft.

30 This separate starter shaft may be the shaft or shank portion of the starting crank usually provided on motor cars and in which case the pulley is connected with the motor shaft through the medium of a one-way driving clutch between the starting crank and motor shaft, the pulley itself having a one-way driving connection with the starting crank. "Back-kick" or reverse rotation of the motor is prevented by the provision of a stationary yoke about the starting crank and having a one-way drive connection with said starting crank arranged the reverse of the one-way drive connections

Other features and the details of construction will appear as the specification proceeds.

60 The accompanying drawing illustrates the invention embodied in practical commercial form, but I would have it understood that various modifications and changes may be made without departing from the 65 true spirit and scope of the invention.

In said drawing:

Figure 1 is a longitudinal sectional view of the invention as applied to a motor of the "Ford" type.

Fig. 2 is a top plan view of the same with 60 the connection to the starting pedal shown broken away.

Figs. 3 and 4 are cross sectional views of the motor shaft clutch and the starter clutch respectively taken substantially on 65 the lines 3-3 and 4-4 of Fig. 1.

Fig. 5 is a broken sectional view of the holding clutch taken substantially on the plane of the line 5-5 of Fig. 1.

In the illustration, 7 designates the motor 70 shaft and 8 the starting crank having a shaft or shank portion 9 journaled in the frame 10 concentric to the end of the motor shaft.

Mounted fast on the starting crank shaft 75 as by means of a suitable key 11 is a driving member in the form of a sleeve 12 carrying a casing 13 surrounding the end portion of the motor shaft. Fastened upon the motor shaft within this casing is a clutch 80 member 14 having a series of tapered or wedge shaped seats 15 in the periphery thereof to receive the rollers 16 which form coupling elements between the driving casing and the clutch member. Springs 17 are 85 shown provided in recesses back of said rollers for thrusting the rollers outward into engagement with the periphery of the inclosing casing. This construction provides a form of wedge clutch which is operative 90 in one direction only.

Also mounted upon the starting crank shaft is a starting pulley or drum 18, said pulley being shown as having a one-way driving connection with the starting crank 95 similar to that just described, and comprising a clutch member 19 fastened on the starting crank shaft as by means of the key 11, and having tapered or wedge seats 20 in its periphery to receive the coupling 100 rollers 21 which are adapted to make engagement with the casing portion 22 of the pulley which surrounds said clutch member 19.

Suitable means are provided for rotating 105 the starting pulley, said means taking the form in the present disclosure, of a flexible connection or cable 23 attached to the periphery of the drum and seated in a groove 24 provided in said drum, said cable pass-

ing over a suitable guide pulley 25 and being connected with a suitable operating lever or other device such as the foot pedal 26. Also connected with the starting pulley there is shown a return cable 27 disposed in a groove 28 and acted upon by a spring 29 to restore the parts after a starting operation.

The operation will be clear from the foregoing, it being seen that pressure on the foot pedal or other operating device rotates the driving pulley toward the right, in Fig. 4, which causes the clutch rollers to bind in the seats 20 provided therefor, thus coupling the starting pulley to the starting crank shaft, and as said starting crank shaft is coupled to the motor shaft by the clutch elements 16 working in a similar direction it will be apparent that the rotation of the drum will be imparted to the motor shaft. If the motor should fail to start at the first operation of the starting pedal, pressure on the pedal is released, the restoring spring returns the parts to original position and the pedal may then be again operated to turn the motor. This operation may be repeated as often as necessary.

The invention does not interfere with starting the motor by means of the starting crank in the usual way, because it will be seen that when the starting crank is operated the drive will be direct from said starting crank and casing 13 through the movable clutch elements 16 and clutch member 14 to the motor shaft, the clutch between the starting pulley and starting crank shaft being inoperative under the circumstances so that the starting pulley is not affected when the starting crank is being used.

40 Backward rotation of the motor is guarded against by means consisting in the present disclosure of a yoke 30 attached to the frame 10 and surrounding the starting crank shaft, said yoke inclosing a clutch member 31 fast on the starting crank shaft having tapered wedge seats 32 faced in the opposite direction from the clutches previously described and arranged to receive the spring pressed clutching rollers 33. By reason of the fact that this holding clutch is faced to operate the reverse of the other clutches, it will be seen that any tendency of the motor to rotate in the wrong direction will be immediately checked. In addition to guarding the operator of the car against injury this holding clutch is of value in that it holds the motor against "dropping back" after having been brought up to the point of "compression," when the foot pedal is released to take hold for a fresh operation. This enables the operator with one operation of the pedal to bring the motor up to compression and then with the next operation of the pedal "spin" the motor over compression point.

The device is readily attachable to cars of the "Ford" type by withdrawing the transverse pin usually provided on the forward end of the motor shaft for engagement with clutch jaws provided on the end of the starting crank shaft, and then slipping the motor clutch member 14 on to the end of the motor shaft and keying it in place thereon as by means of the transverse pin 34 which was formerly used for engagement by the starting crank. The holding clutch yoke is readily applied to the motor frame as by bolting it thereto, and the sleeve 12 and clutch elements 19 and 31 are readily applied to the starting crank shaft as by keying said parts thereto as indicated. The starting lever or pedal 26 may be mounted wherever convenient and the spring tensioned returning cable 27 may be attached to any convenient abutment.

The starting pedal illustrated is of novel construction in that it is provided with a spiral cam 26' over which the starting cable rides, said cable being attached to the lower end of the cam so that in the first portion of the stroke of the pedal this low portion of the cam will be effective and the leverage force will be greatest and so that as the higher portions of the cam become effective, a more rapid movement will be imparted to the starting drum and hence to the motor. This provides the leverage necessary for an easy starting movement, and provides for a certain degree of acceleration after the initial movement is begun.

The clutch connection with the motor shaft may be protected by means of an inclosing casing such as indicated at 35.

I claim:

1. Motor starting mechanism comprising in combination with a motor shaft, a starting crank journaled in concentric relation to the motor shaft, a one-way drive connection from said starting crank to the motor shaft, a motor starting member and a one-way drive connection from said motor starting member to the starting crank.

2. Motor starting mechanism comprising in combination with a motor shaft, a starting crank journaled in concentric relation to the motor shaft, a one-way drive connection from said starting crank to the motor shaft, a motor starting member and a one-way drive connection from said motor starting member to the starting crank, a relatively fixed stop member and a one-way drive connection from said stop member to the starting crank arranged to prevent reverse movement of said starting crank.

3. Motor starting mechanism comprising in combination with a motor shaft, a starting crank journaled concentrically thereto, a starting member journaled on said starting crank, a one-way drive connection from said starting member to said starting crank.

and a one-way drive connection from the starting crank to the motor shaft.

4. Motor starting mechanism comprising in combination with a motor shaft, a starting crank journaled concentrically thereto, a starting pulley journaled on said starting crank, a one-way drive connection from said starting pulley to said starting crank, a flexible connection engaged with said pulley for 10 rotating the same in a motor starting direction, a spring operated connection with said pulley for returning the same after operation by said flexible connection, and a one-way drive connection from the starting 15 crank to the motor shaft.

5. Motor starting mechanism comprising in combination with a motor shaft, a starting crank journaled concentrically thereto, a sleeve fast on said starting crank, one-way 20 drive connections from said sleeve to the motor shaft, a starting pulley journaled on said sleeve, means for rotating said starting pulley and one-way drive connections from said starting pulley to the starting crank.

25 6. Motor starting mechanism comprising in combination with a motor shaft, a starting crank journaled concentrically thereto, a sleeve fast on said starting crank, one-way drive connections from said sleeve to the 30 motor shaft, a starting pulley journaled on said sleeve, means for rotating said starting pulley and one-way drive connections from said starting pulley to the starting crank, a fixed holding frame and one-way holding 35 connections from said frame to the starting crank arranged to prevent reverse rotation of said starting crank.

7. Motor starting mechanism comprising in combination with a motor shaft, a starting 40 crank journaled concentrically thereto, a driving casing carried by the starting crank and inclosing the end of the motor shaft, a clutch element on the motor shaft within said casing and provided with tapered roller 45 seats in the periphery thereof, rollers engaged in said seats and providing a one-way coupling with the motor shaft, a driving pulley journaled on the starting crank having a driving casing surrounding the 50 same, a clutch member on the starting crank within said casing provided with wedging roller seats in the periphery thereof, rollers engaged in said seats and means for rotating the starting pulley.

55 8. Motor starting mechanism comprising in combination with a motor shaft, a starting crank journaled concentrically thereto, a driving casing carried by the starting crank and inclosing the end of the motor 60 shaft, a clutch element on the motor shaft within said casing and provided with tapered roller seats in the periphery thereof, rollers engaged in said seats and providing a one-way coupling with the motor shaft, 65 a driving pulley journaled on the starting

crank having a driving casing surrounding the same, a clutch member on the starting crank within said casing provided with wedging roller seats in the periphery thereof, rollers engaged in said seats, a cable engaged with the starting pulley for rotating it in one direction and a spring tensioned return cable connected with the pulley for returning it in the opposite direction to a position of rest. 75

9. Motor starting mechanism comprising in combination with a motor shaft, a starting crank journaled concentrically thereto, a driving casing carried by the crank shaft and inclosing the end of the motor shaft, a 80 clutch element on the motor shaft within said casing and provided with tapered roller seats in the periphery thereof, rollers engaged in said seats and providing a one-way coupling with the motor shaft, a driving pulley journaled on the starting crank having a driving casing surrounding the same, a clutch member on the starting crank within said casing provided with wedging roller seats in the periphery thereof, rollers 85 engaged in said seats and means for rotating the starting pulley, a yoke surrounding the shank of the starting crank, a clutch member on the starting crank within said yoke and provided with roller seats tapered 90 reversely to the roller seats aforementioned, and rollers engaged in said latter reversely disposed seats.

10. Motor starting mechanism comprising in combination with a motor shaft, a 100 starter shaft disposed concentrically thereto, a casing on said starter shaft surrounding the end of the motor shaft, a clutch member on the motor shaft within said casing, one-way clutching elements between said casing 105 and said clutch member, a starting pulley rotatably engaged on the starter shaft, a clutch member on the starter shaft, one-way clutching elements between said pulley and said clutch member on the starting shaft, 110 and means for rotating said starting pulley.

11. Motor starting mechanism comprising in combination with a motor shaft, a starter shaft disposed concentrically thereto, a casing on said starter shaft surrounding the 115 end of the motor shaft, a clutch member on the motor shaft within said casing, one-way clutching elements between said casing and said clutch member, a starting pulley rotatably engaged on the starter shaft, a 120 clutch member on the starter shaft, one-way clutching elements between said pulley and said clutch member on the starter shaft, and means for rotating said starting pulley comprising a starting cable engaged with 125 the pulley for rotating the same in one direction, and a spring tensioned return cable engaged with the pulley for rotating it in the reverse direction.

12. Motor starting mechanism comprising 130

in combination with a motor shaft, a starter shaft disposed concentrically thereto, a casing on said starter shaft surrounding the end of the motor shaft, a clutch member 5 on the motor shaft within said casing, one-way clutching elements between said casing and said clutch member, a starting pulley rotatably engaged on the starter shaft, a clutch member on the starter shaft, one-way clutching elements between said pulley and said clutch member on the starter shaft, and means for rotating said starting pulley, a holding yoke about the starter shaft, a clutch member on the starter shaft within 10 said holding yoke, and one-way holding connection between said yoke and said last

mentioned clutch member for preventing reverse rotation of the starter shaft.

13. Motor starting mechanism comprising in combination with a motor shaft, a starting shaft concentric thereto, a member carried by the starting shaft and surrounding the end of the motor shaft, a one-way driving clutch between said surrounding member and the motor shaft, a starting member 20 engaged on the starting shaft, a one-way driving clutch between said member and the starting shaft, and a protective housing carried by said member and covering the clutch connection between the motor shaft and the member on the starting shaft. 25

GEO. L. GRIFFITH.
